UNITED STATES PATENT OFFICE.

EUGENE M. FISHELL, OF CLEVELAND, OHIO, ASSIGNOR TO THE NATIONAL CARBON COMPANY, OF SAME PLACE.

VOLTAIC CELL.

SPECIFICATION forming part of Letters Patent No. 655,968, dated August 14, 1900.

Application filed January 20, 1900. Serial No. 2,092. (No model.)

To all whom it may concern:

Be it known that I, EUGENE M. FISHELL, a citizen of the United States, residing at Cleveland, in the county of Cuyahoga and State of Ohio, have invented a certain new and useful Improvement in Voltaic Cells, of which the following is a full, clear, and exact description, reference being had to the accompanying drawings.

10 My invention relates to the class of voltaic cells which have as one element a porous carbon-cup which is adapted to contain a depolarizing agent; and its primary object is to provide such a cup having a relatively-great 15 generating area and which will be at the same time of compact and serviceable form, all of which will be more fully described hereinafter and definitely set forth in the claims.

The drawings clearly illustrate my invention.

Figure 1 represents a vertical section of the cell complete, the containing-jar being shown in dotted lines. Fig. 2 is a side elevation, partly broken away, of the cup. Fig. 3 is a 25 cross-section of the cup.

Referring to the parts by letters, A represents the carbon-cup, which has a head a and two depending walls a' a'' , one within the other. In its preferred form the cup is 30 circular in cross-section. The head at the upper end of the cup extends beyond the outer wall a' in the form of a flange a^3 , by which it is adapted to be carried by the containing-jar.

B. The head also carries an upwardly-projecting lug a^4 integral therewith, in which is mounted the binding-post E. Through the walls of the cup a vertical opening a^5 is formed, which connects the interior bore a^9 with the exterior of the cup through the integral connecting-sleeve a^6 , whereby the surrounding fluid may circulate freely. The cavity between the outer and inner walls is filled with a depolarizing agent G, such as manganese dioxide, held in place by the plug C, which 45 may be of cement or other material. A hole a^7 is formed through the head concentric with the bore a^9 , and preferably smaller, and through this hole passes the bar D of zinc or

an equivalent voltaic element, this bar being insulated from the cup by the bushing F. 50 The zinc D carries a collar d, which supports it within the bushing, and a binding-screw d' , which affords means for electrical connection. In practice I may provide vents from the cavity through the cup, as shown in dotted lines at a^8 .

From the above it is readily seen that a cell constructed in accordance with my invention presents without materially increasing the bulk of the cell at once a greatly-increased 60 area of generating-surface (with the consequent desideratum of a reduced internal resistance) and a depolarizer acting very effectively on the whole generating-surface.

Having described my invention, I claim— 65

1. In a voltaic cell, a porous carbon-cup consisting of a head having extending from it integrally two continuous walls one within the other, there being aligned openings through said two walls, and a sleeve integral with said 70 walls and connecting said openings, substantially as described.

2. In a voltaic cell, a porous carbon-cup consisting of two continuous cylindrical walls one within the other uniting at their upper end 75 to form a head, said head having a laterally-projecting annular flange, said walls being pierced by a vertical opening surrounded by a sleeve, said sleeve lying between and being integral with the walls of the cup, substantially as described.

3. In a voltaic cell, a porous carbon-cup consisting of a head having extending from it integrally two continuous walls, one within the other, there being aligned vertically-elongated openings through said two walls, and a sleeve integral with said walls and connecting said openings, the wall of said sleeve at its upper side uniting with said head, substantially as specified. 85

In testimony whereof I hereunto affix my signature in the presence of two witnesses.

EUGENE M. FISHELL.
